ELECTRICAL WASHER FOR EMULSIONS

Harmon F. Fisher, Long Beach, Calif., assignor
to Petroleum Rectifying Company of California, Los Angeles, Calif., a corporation of California

Application October 25, 1926, Serial No. 143,933
Renewed September 10, 1932

19 Claims. (Cl. 204—24)

My invention relates to the petroleum industry and particularly to a method of and apparatus for washing petroleum. Petroleum as it is taken from wells usually has water associated therewith in the form of small particles which cannot be separated therefrom by gravitation. The emulsion consisting of petroleum and water must therefore be subjected to a dehydrating process so that the petroleum will be freed of its water content and rendered commercially valuable. The emulsion quite often carries suspended particles of mud, sand, silt and the like, the presence of which is quite objectionable. These particles which may be conveniently termed "foreign matter" tend to clog up the pipes and fill the dehydrator tank and also to cause corrosion of the apparatus. I have found that by utilizing the principle of cataphoresis that the foreign matter may be swept from the petroleum.

It is accordingly an object of this invention to provide a method of cleaning petroleum, which method utilizes among other principles the principle of cataphoresis.

Another object of this invention is to provide an apparatus for conducting the method.

My invention is carried on by passing the petroleum through an electric field. By the term "petroleum" is meant a petroleum having a water content or having no water content. In other words, the term "petroleum" refers to a fluid in which the principal constituent is petroleum. In passing through the electric field the suspended particles of foreign matter are bombarded by charged liquid particles so that a definite electrical high potential charge is given to them. The particles of foreign matter thus being charged are carried under the influence of the electric field to the electrode of lowest field intensity where they are collected.

It is accordingly an object of this invention to provide an apparatus in which the foreign matter is bombarded by charged particles.

I have found that in most instances it is desirable to provide a collecting liquid or a vehicle at the electrode of lowest field intensity for collecting the particles of foreign matter and for removing them from the apparatus.

It is accordingly an object of this invention to provide an electrical cleaning apparatus for petroleum in which the foreign particles are collected and removed from the apparatus by means of a suitable vehicle.

By using for the ionic bombardment liquid dissimilar to the oil but having a particular affinity for the foreign matter in suspension, the vehicle

could be dispensed with, since the liquid used for the ionic bombardment will collect on the electrode of lowest field intensity and thus serve itself as a vehicle.

It is accordingly one of the objects of my invention to provide a cleaning apparatus for petroleum in which a charging liquid dissimilar to the petroleum and having a greater affinity for the foreign matter than the oil, is used for forming the charged particles.

Other objects and advantages of the invention will be made evident hereinafter.

Referring to the drawing which is for illustrative purposes,

Fig. 1 is a vertical section through a preferred form of the invention.

Fig. 2 is an enlarged fragmentary section of the upper end of the electrode of the highest field intensity.

Fig. 3 is a fragmentary section showing the important part of an alternative form of the invention.

Referring to Figs. 1 and 2 of the drawing, the treater of my invention consists of a shell 11 supporting an inner coating 10 and having a tight top 12 and a tight bottom 13, these parts cooperating to provide a chamber 14. This coating 10 is made of a material having an affinity for the carrier fluid, as will be hereinafter pointed out, such a material being plaster of Paris, or certain other cements having such a characteristic. The shell 11 serves as a grounded electrode for the apparatus for the treater and is the electrode of lowest field intensity. Supported centrally by the tight top 12 is an insulator 16 through which a tube 17 is extended. A tank 18 is supported at the upper end of the tube 17. The lower end of the tube 17 is extended into the chamber 14 and supported at the lower end thereof is a central live electrode 20 which is the electrode of highest field intensity of the treater.

Referring to Fig. 2, the lower end of the tube 17 is threaded and a nut 21 is screwed thereonto. The nut 21 carries a hood 22 and a sleeve 23. These parts are spaced a distance from each other so as to provide an annular outlet passage 25 which is curved downward at its periphery. The nut 21 is provided with a central chamber 26 which is connected to the interior of the tube 17. The chamber 26 is connected by openings 28 to the annular passage 25. Threadedly attached at 30 to the lower part of the nut 21 is a rod 31. Placed on the rod 31 are discs 33 providing edges 34, and sleeves 35. These parts are alternately arranged as shown clearly in Figs. 1

and 2 and are preferably formed of a material having an affinity for a fluid which is flowed therealong. A nut 36 is threadedly secured to the lower end of the rod 31 for clamping the 5 discs and sleeves 33 and 35 on the rod 31. Petroleum to be treated is introduced into the upper end of the chamber 14 through a petroleum inlet pipe 38 which is attached to the tight top 12 of the treater and communicates with the 10 perforated annular pipe 39. An annular trough member 40, as shown in Fig. 1, is located at the upper end of the chamber 14. This annular trough member 40 provides an annular trough 41 in communication with which is a vehicle 15 fluid supply pipe 42. The annular trough 41 communicates with the chamber 14 through a narrow annular mouth 43. An outlet pipe 45 is connected to the lower part of the chamber 14 through the tight bottom 13 of the treater. The 20 central electrode 20 and the shell 11 which serves as the outer electrode are connected in an electric circuit by a conductor 48 this circuit including a direct current electricity source, as indicated at 25 49. One side of the source 49 is grounded and the shell 11 is also grounded so that it is at ground potential, the central electrode 20 being the electrode of greater field intensity. The central electrode 20 is preferably the negative electrode, whereas the shell 11 is the positive electrode. 30

The operation of the invention is substantially as follows:

The circuit to the electrodes is completed and an electric field is established in the chamber 14 35 between these electrodes. The field radiates from the central electrode 20; therefore, this electrode is the electrode of greatest field intensity. The petroleum carrying particles of foreign matter which may be carbon, mud, sand, silt, or the like, is introduced into the chamber 14 at its upper 40 end by means of the annular pipe 39. The annular pipe 39 assures an even distribution of the petroleum in the chamber 14. The tank 18 is filled with a charging fluid which may be water 45 or any other suitable electrolyte. This charging fluid flows downward through the tube 17 and passes onto the outer face of the electrode 20 through the annular passage 25. The shape of the 50 annular passage 25 is such as to direct the charging fluid downward along the face of the electrode 20 in the form of a fluid envelope, as indicated by light lines 53 in Fig. 2.

By forming the electrode 20 from a material having an affinity for the charging fluid, this 55 fluid will hug closely to the outer face thereof, as indicated in Fig. 2. The edges 34 of the discs 33 provide zones of very great field intensity. As the charging fluid passes over the edges 34 the intense field at these zones break up the liquid 60 into charged particles as indicated at 55 in Fig. 2. These charged particles are preferably of fixed sign, and in the preferred embodiment are negatively charged, as is also the electrode 21, and are therefore attracted by the positive electrode or 65 shell 11 of the treater. These charged particles 55 are therefore impelled rapidly through the chamber 14 towards the shell 11. These charged particles 55, as it should be clearly understood, are continually given off or driven from the 70 charging fluid 53 along the entire length of the central electrode 20. These charged particles 55 bombard the particles of foreign matter carried in suspension in the petroleum, giving them a definite electrical high voltage charge so that they too are carried outward by the influence of

the electric field towards the shell 11. The vehicle liquid which is introduced into the trough 41 by the pipe 42 is directed downward by the mouth 43 in a thin coating 57 along the coating 10, as shown in Fig. 1. The charged particles upon 5 reaching the shell 11 are forced into and are absorbed by the vehicle coating 57. The vehicle coating 57 therefore serves the purpose of holding the collected particles of foreign matter to the shell 11 and of carrying them from the 10 treater. The petroleum upon reaching the lower end of the treater will be completely cleaned of foreign matter. The petroleum, charging fluid and the vehicle carrying the foreign matter will all pass from the treater through the pipe 45. 15

By reason of the fact that the vehicle 57 has a greater affinity for the foreign matter than the petroleum has for it, the petroleum may be readily separated therefrom in a settling tank. In some instances I have found that it is unnecessary to provide the vehicle coating 57. This is because of the fact that the charging liquid may have a high affinity for the foreign matter and may be introduced to such an extent that it will serve as a vehicle upon reaching the shell 11. 20 25

From the foregoing description it will be seen that my invention utilizes the principle of cataphoresis for cleaning oil; that is, the introduction of charged particles, which charged particles charge the particles of foreign matter, thus causing them to travel under the influence of an electric field to one of the electrodes. When my invention is used, the petroleum is thoroughly cleaned of foreign matter and may be very readily dehydrated. It is found that when the foreign matter is removed, not only is the clogging and corrosion of the dehydrating apparatus eliminated but the petroleum is much easier to dehydrate. The forming of the central electrode 20 from a material having an affinity for the charging 30 liquid is an important auxiliary feature of the invention since it causes the charging liquid 53 to adhere to the surface thereof along its entire length.

Referring to Fig. 3, I will describe the alternative form of the invention. In this form of the invention the insulator 16 supports a rod 70 at the lower end of which an inverted cone 71 is placed. The central electrode 20 is supported by the tube 17 which is connected to the inverted cone 71. 40 Charging fluid is introduced into the cone 71 by means of a perforated ring 73 which is supplied with charging fluid by a pipe 74 which extends to the exterior of the shell 11 through the tight top 12. The perforated ring pipe 73 is spaced a 45 50 distance above the inverted cone or baffle 71 and the charging fluid is allowed to fall into the baffle 71 in the form of drops so that the high tension path of the apparatus will be in no way connected to the grounded part of the apparatus. 55 This last form of the invention locates all of the parts of the apparatus which are "high tension" inside the shell 11, of course with the exception of the upper end of the rod 70 which is connected to the source of electrical energy. 60 65

Certain phases of the subject-matter disclosed in this application, and not herein claimed, are disclosed and claimed in my co-pending application entitled "Dehydrator with high field intensity grounded electrode", filed September 16, 70 1926, Serial No. 135,804.

I claim as my invention:

1. A method of removing foreign matter from petroleum or other oil, comprising: passing the oil through an electric field; sending charged

- particles of a charging fluid into said oil so as to give the particles of foreign matter a definite charge; and collecting said particles of foreign matter in a vehicle fluid.
5. 2. A method of removing foreign matter from petroleum or other oil, comprising: passing the oil through an electric field; sending charged particles of a charging fluid into said oil so as to give the particles of foreign matter a definite charge; and collecting said particles of foreign matter in a vehicle fluid, the affinity between said vehicle fluid and said foreign particles being greater than the affinity between said oil and said vehicle fluid.
10. 3. In a treater for removing foreign particles from petroleum, the combination of: an outer electrode; an inner electrode, there being an electric field between said electrodes; means on said inner electrode for creating zones of high field intensity; means for directing a charging fluid adjacent said inner electrode; and means for supplying a liquid to be treated into said electric field.
15. 4. In a treater for removing foreign particles from petroleum, the combination of: an outer electrode; an inner electrode, there being an electric field between said electrodes; means on said inner electrode for creating zones of high field intensity; means for directing a charging fluid adjacent said inner electrode; means for supplying a vehicle liquid adjacent said outer electrode; and means for supplying a liquid to be treated into said electric field.
20. 5. A method of removing foreign matter from petroleum or other oil which comprises: impressing on said oil an electric field; and bombarding said foreign matter with charged particles of a liquid dissimilar to said oil and having a greater affinity for said foreign matter than for said oil, whereby said foreign matter is withdrawn from said oil through the action of said field.
25. 6. A method of removing foreign particles from petroleum or other oil which comprises: forming an electric field of non-uniform intensity between a pair of electrodes; passing a charging fluid through that portion of the field of greatest intensity and in contact with one of said electrodes, whereby charged particles of said charging fluid are projected toward the other of said electrodes; passing a vehicle fluid in contact with the other of said electrodes; and passing said oil between said charging fluid and said vehicle fluid, whereby particles of foreign matter carried by said oil are bombarded and drawn into contact with said vehicle fluid.
30. 7. In an electric treater for treating petroleum the combination of: an electrode providing a zone of high field intensity; means for passing a fluid envelope of a charging fluid around and in contact with said electrode, whereby said fluid passes through said zone of high field intensity in such a manner that charged particles of said charging fluid are projected in a direction away from said electrode; and means for passing petroleum to be treated through the path of travel of said charged particles.
35. 8. In combination in an electrical treater: an electrode of high field intensity; an electrode of low field intensity, there being a treating space between said electrodes; means for passing a primary fluid along said electrode of high field intensity; means for passing a secondary fluid along said electrode of low field intensity; and means for introducing a tertiary fluid into said

treating space between said secondary and primary fluids.

9. A combination as defined in claim 8 in which said electrodes are coated with a material having an affinity for said primary and secondary fluids to cause said primary and secondary fluids to respectively cling to said high and low field intensity electrodes.

10. A method of treating petroleum to remove a solid foreign matter therefrom, which includes the step of bombarding said petroleum with charged particles of like sign in the presence of a unidirectional electric field; and collecting said solid foreign matter.

11. A method of removing foreign matter from a fluid, which includes the steps of: subjecting said fluid and its associated foreign matter to the action of an electric field; sending charged particles of a charging fluid into said fluid with sufficient velocity that said charged particles bombard the particles of foreign matter and impart thereto a definite charge; and collecting said particles of foreign matter.

12. A method of treating petroleum, including the steps of: passing a stream of charging fluid along an electrode surface; forming an electric field adjacent said electrode surface and of such intensity adjacent said electrode surface that charged particles of said charging fluid are violently propelled from said stream of charging fluid; and subjecting the petroleum to be treated to said electric field and to said bombarding action.

13. A method of treating petroleum, including the steps of: passing a stream of charging fluid around an edge of an electrode surface; forming a unidirectional electric field adjacent said electrode surface and of such intensity adjacent said edge of said electrode surface that charged particles of said charging fluid are violently propelled from said stream of charging fluid; and subjecting the petroleum to be treated to said electric field and to said bombarding action.

14. In an electric treater, the combination of: a live central electrode; a surrounding electrode, there being a treating space therebetween; nozzle means for supplying a fluid envelope of charging fluid around and in contact with said live central electrode; a charging-fluid storage means in communication with said nozzle means; and means for delivering the fluid to be treated into said treating space.

15. In an electric treater, the combination of: a central electrode; a surrounding electrode, there being a treating space therebetween; nozzle means adjacent one end of said central electrode and guiding a stream of fluid adjacent the surface of said central electrode, said fluid forming a fluid envelope around and in contact with said central electrode; and pipe means communicating with said nozzle means and extending away from said one end of said electrode.

16. A process which includes the steps of: setting up an electric field between a pair of electrodes; flowing a stream of liquid along one of said electrodes; and simultaneously flowing petroleum between the other of said electrodes and said stream of liquid whereby foreign particles in said petroleum are moved toward and into said stream of liquid.

17. In a treater for removing foreign particles from emulsion, the combination of: outer and inner electrodes providing surfaces formed of a material having an affinity for a charging fluid,

there being an electric field between said electrodes; means on said inner electrode for creating zones of high field intensity; means for flowing said charging fluid adjacent said central electrode; and means for supplying a liquid to be treated into said electric field.

18. In an electric treater, the combination of: a shell comprising an electrode; a live central electrode extending centrally into said shell but insulated therefrom; means for setting up an electric field between said electrodes, said field being sufficiently more intense adjacent said central electrode than adjacent said shell whereby charged liquid particles are violently expelled from said central electrode and toward said shell; and means for flowing a liquid along the inner

surface of said shell and including an annular trough member cooperating with said inner surface of said shell in providing a narrow annular mouth.

19. In an electric treater, the combination of: 5 a shell; a central electrode extending axially into said shell but insulated therefrom, there being an electric field between said central electrode and said shell; annular means for introducing a fluid into said shell; and a baffle means 10 in the path of travel of said fluid and directing said fluid around said central electrode in the form of a fluid envelope contacting and flowing along said central electrode.

HARMON F. FISHER.
